(57) **CLAIM**

The ornamental design for a charging box with earphones, as shown and described.

DESCRIPTION

FIG. 1 is a front view of a charging box with earphones in an open state, showing the new design.

FIG. 2 is a back view of the charging box with earphones in an open state;

FIG. 3 is a left view of the charging box with earphones in an open state;

FIG. 4 is a right view of the charging box with earphones in an open state;

FIG. 5 is a top view of the charging box with earphones in an open state;

FIG. 6 is a bottom view of the charging box with earphones in an open state;

FIG. 7 is a perspective view of the charging box with earphones in an open state;

FIG. 8 is a front view of the charging box in a closed state;

FIG. 9 is a back view of the charging box in a closed state;

FIG. 10 is a left view of the charging box in a closed state;

FIG. 11 is a right view of the charging box in a closed state;

FIG. 12 is a top view of the charging box in a closing state;

FIG. 13 is a bottom view of the charging box in a closed state; and,

FIG. 14 is a perspective view of the charging box in a closed state.
